US00D425980S

United States Patent [19]

Last et al.

[11] Patent Number: Des. 425,980

[45] Date of Patent: ** May 30, 2000

[54] **HAND-HELD TISSUE EXAMINATION DEVICE**

[75] Inventors: **Timothy E. Last**, Hopedale; **Brian D. Noble**, Shrewsbury; **Troy W. Roberts**, Pepperell; **Alan D. Ball**, Arlington; **Thomas Swyst**, Arlington; **Andrew P. Tosh**, Arlington; **Philip C. Walker**, Arlington, all of Mass.

[73] Assignee: **Assurance Medical, Inc.**, Hopkinton, Mass.

[**] Term: **14 Years**

[21] Appl. No.: **29/078,243**

[22] Filed: **Oct. 20, 1997**

[51] LOC (7) Cl. **24-02**

[52] U.S. Cl. **D24/107**

[58] Field of Search **D24/107, 153, D24/177, 186; 600/478, 476, 410, 300, 310, 437, 445, 446, 587, 407; 128/898, 903, 920**

[57] **CLAIM**

The ornamental design for a hand-held tissue examination device, as shown and described.

DESCRIPTION

FIG. 1 is a front perspective view of a hand-held tissue examination device;

FIG. 2 is a back elevational view thereof;

FIG. 3 is a front elevational view thereof;

FIG. 4 is a right side elevational view thereof;

FIG. 5 is a left side elevational view thereof;

FIG. 6 is a top elevational view thereof;

FIG. 7 is a bottom elevational view thereof; and,

FIG. 8 is a bottom perspective view thereof.
